Primary Examiner — Robin V Webster*Assistant Examiner* — Rachel Voorhies(74) *Attorney, Agent, or Firm* — Burbage Law, P.C.;
Jon-Michael Burbage(57) **CLAIM**

The ornamental design for a camera module, as shown.

DESCRIPTION

FIG. 1 is a front perspective view of the camera module;
 FIG. 2 is back perspective view thereof;
 FIG. 3 is a front view thereof;
 FIG. 4 is a back view thereof;
 FIG. 5 is a right side view thereof;
 FIG. 6 is a left side view thereof;
 FIG. 7 is a bottom view thereof; and,
 FIG. 8 is a top view thereof.

The broken lines in the drawings illustrate portions of the camera module which form no part of the claimed design.

1 Claim, 7 Drawing Sheets(56)
